(57) **CLAIM**

The ornamental design for a keyboard, as shown and described.

DESCRIPTION

FIG. 1 is a perspective view of a keyboard showing our new design;

FIG. 2 is a top view thereof;

FIG. 3 is a first side view thereof;

FIG. 4 is a second side view thereof;

FIG. 5 is a rear view thereof;

FIG. 6 is a front view thereof;

FIG. 7 is a bottom view thereof;

FIG. 8 is a perspective view of a keyboard showing an alternative embodiment of our new design;

FIG. 9 is a top view thereof;

FIG. 10 is a first side view thereof;

FIG. 11 is a second side view thereof;

FIG. 12 is a rear view thereof;

FIG. 13 is a front view thereof; and,

FIG. 14 is a bottom view thereof.

The broken line regions in FIGS. 1–14 showing the remainder of the device are for illustrative purposes only and form no part of the claimed design.

The broken line showing of portions of the controller no part of the claimed design.
